Section 1, Public Law 690, August 8, 1946
Patent expires May 26, 1964

4 Claims. (Cl. 179—15)

1

The present invention relates to multi-channel electrical pulse communication systems.

In systems of the type specified the channels are discriminated by the times of occurrence of the respective pulses within a cyclic period and the intelligence of a channel is transmitted as a modulation of the pulses, for example the pulses of a channel are time-phased within predetermined time intervals in accordance with the instantaneous amplitude of the signal wave of that channel. Arrangements for successively and cyclically bringing the channels into use are known as distributors, there being normally a distributor at the transmitting and receiving ends of the system working in co-operation.

The distributor may take the form of a delay network. Such a network may comprise a four terminal passive transmission network or artificial line which retards the passage of an electrical current propagated therethrough, and comprises a plurality of series connected cells made up of electrical condensers and inductances and preferably alike each of which retards the current by predetermined, preferably equal time intervals. If an electrical pulse is applied to the input terminals of the delay network, at various tapping points along the network pulses may be obtained which are delayed by time intervals depending upon the number of cells through which the pulse has passed up to a specified tapping point. The pulses obtained at the various tapping points are then applied to bring the channels of a multi-channel system successively into use. If the network has a large number of cells and theoretically, an infinite number, then being equivalent to a transmission line, the pulses suffer very little distortion.

For a delay network having a delay of 100 microseconds and utilising a pulse of rectangular waveform of 5 microseconds' duration, the distortion is small if the cut-off frequency of the network is greater than, for example 10 megacycles and consists of some 3000 cells. Such a number of cells is too great for practical purposes, and the fewer the cells for the same delay, the greater the distortion of the pulses which involves the shaping and timing of the pulses and their durations with consequential effects on the time-phasing and periods of the channels resulting in interference, cross-talk between adjacent channels and noise. The object of the present invention is to utilise a practical number of cells and to provide means to compensate or eliminate the effects due to distortion.

The present invention accordingly provides a

2

multi-channel electrical communication system utilising a distributor comprising a delay network and means for applying to said network a regularly repeated wave form and means for connecting points on said network to the respective channel apparatus by means for compensating or eliminating effects due to distortion of said wave form as said wave form travels along said network. In a practical case the said wave form may consist of a sawtooth wave form, rectangular wave form or pulses whose durations may determine a channel period, that is, the portion of each distributor cycle allotted to the respective channels.

Other features and aspects of the invention are defined in the appended claims.

The invention will be better understood from the following description taken in conjunction with the accompanying drawings in which:

Figure 1 shows various graphical curves used in the description and

Figure 2 shows schematically the circuit arrangements of one embodiment of the invention.

Figure 3 shows in block schematic form another embodiment of the invention and

Figure 4 are explanatory curves used in the description of Figure 3.

The distortion of the pulses produced by a delay network involves an increase in the pulse duration due to the fact that the instant of commencement of the pulse is advanced and the instant of termination of the pulse is retarded, with respect to the mean pulse time. This is illustrated in Figure 1. A pulse of rectangular wave form as shown at *a*, Figure 1, is applied to the input terminals of the delay network, for example as shown at *1*, Figure 2, and as the pulse travels along the network, the leading and trailing edges of the pulse become less and less inclined to the time axis and the duration of the pulse is increased, as shown at *b*, *c*, *d*, and *e*, Figure 1, which show the pulses at successive points along the delay line. Owing to attenuation in the inductance coils, the amplitude of the pulse gradually decreases and the pulse proceeds along the network. Further oscillations at the cut-off frequency of the network appear as shown in curves *d* and *e*, Figure 1, and may distort the leading and trailing edges of the pulse, as shown in curve *f*, Figure 1.

It will be seen therefore, that the time intervals between the commencements of successive pulses tapped off from like sections or cells of the delay network grow successively smaller from the input to the output end of the network and the beginning and end of the pulses get more and more indefinite. Consequently when the pulses ob-

tained from the delay network are employed directly, for example, to trigger or gate respective circuits which brings the channels into successive use, the timing of the gating or triggering pulses is not sufficiently precise for an efficient multi-channel system.

This difficulty is not overcome by re-shaping the distorted pulses into rectangular pulses, for even so, the leading and trailing edges of the re-shaped pulses are displaced with respect to the edges of the original pulse. This will be clear from *e*, Figure 1, where the reshaped pulse is shown at *p*. It can be seen that the leading edge *e*' is in front of the leading edge *e* of the original pulse and the trailing edge *t*' of the re-shaped pulse *p* follows the trailing edge *t* of the original pulse.

It has been found, however, that the width of the pulses at approximately half the pulse amplitude, that is represented by the ordinate of the line *y*—*y* in Figure 1, remains substantially invariable at all points along the delay network providing this latter is not too long and occurs at the correct time intervals, that is, at equal time intervals for similar cells between the tapping points of the delay network. According to a feature of the invention, pulses preferably of rectangular wave form, are derived under the control of the distorted pulses, in such manner that the derived pulses are synchronised as to their leading edges or trailing edges to the voltage value which the distorted pulses pass through at the correct moment that is the moment at which the leading or trailing edge would occur in the absence of distortion.

This feature may be carried out in practice, for example as illustrated in Figure 2, by applying the distorted pulses to the grid of a valve amplifier which is suitably biassed so that the valve commences to pass current only at the said voltage value occurring at the correct moment in the duration of the distorted pulse. If the amplitude remains substantially constant this voltage value is approximately the mid-amplitude voltage of the pulse.

In Figure 2 the delay network is shown as comprising a plurality of series connected cells comprising series inductance 2 and shunt capacities 3. Mutual inductance between adjacent coils may be employed if desired. The construction of such network is, of course, well known. The cells are made alike and are designed to have the desired time delay constant so that if a tapping is taken every *m* cells, for example, and a pulse is applied to the input terminals 4, the pulses at the tapping points 5, 6, 7 and so on will be delayed or time phased with respect to each other, in the absence of distortion, by equal intervals of time, which has hereinbefore been called the channel period. During the channel period, the intelligence waves of the respective channels are transmitted.

As pointed out hereinbefore, when few cells are used for long delays, distortion of the pulses is produced and in order to remove the effects of the distortion the outputs from the tapping points 5, 6, 7, etc. are applied to the control grid of an amplifying electron discharge device 10 arranged to function as a constant current device which is so biassed as indicated by the voltage source 11 that the device 10 commences to pass current only at the relevant voltage of the distorted pulse. The valve 10 is preferably a pentode and the constant current is obtained by the help of resistance 12 which has as high a value

as possible. The resistance 12 is usually sufficient alone but a diode connected between cathode and earth on a fixed potential as shown in broken line in channel 5 may be added to give an improvement. The voltage source 11 may be of any adjustable type, and is illustrated only schematically as a battery source. The amplitude of the pulses applied to valve 10 should be considerably greater than the grid cut-off bias

10 of the valve and the pulses obtained from the tapping points of the delay network may therefore require amplification. If a power pulse generator of the kind described in the specification of my co-pending United States application, Serial No. 602,450, filed June 30, 1945, now abandoned, for "Generators of short duration electrical pulses" is employed amplification will not be necessary. Pulses of rectangular wave form may be obtained in the anode or cathode circuit 20 of valve 10. In this way, a slice, so to speak, of the distorted pulses at the mid-voltage or other relevant voltage level of the pulse is in effect obtained and amplified. The pulses obtained from the output of the valve 10 (from the anode circuit as shown in Fig. 2, but they may be taken from the cathode circuit depending upon the sign of the required pulse) are then applied to control in the desired manner the apparatus 25 pertaining to the allotted channel and indicated generally by the blocks 13—17. The blocks 13—17 may represent apparatus at the receiver or transmitter. By way of example a time-phase pulse modulator is shown in block 15 of channel 7.

35 If the distributor is at the receiver, the valve 13 may be desirable to produce a rectangular pulse to maintain open a "gate" circuit during the channel period. At the transmitter the valve 10 may be desirable to shape the pulse to produce for example, trapezoidal wave forms for modulation purposes as described in the specification of my co-pending United States application, Serial No. 602,804, filed July 2, 1945 for "Multi-channel electrical pulse communication systems." In this case a network is included in the anode or cathode circuit of the valve 10.

In cases where no shaping of the pulse is required, that is when the leading or trailing edge only is required to effect an operation the 40 valve 10 can be omitted. In this case the leading or trailing edge of the "slice" is used to trigger a multivibrator circuit and the time modulation is produced by and in the multivibrator itself an example of which will now be given.

55 This pulse modulator comprises a multivibrator circuit arrangement 18 consisting of two interconnected valves 19 and 20 and designed to have one stable condition. Assuming the application of positive pulses to the delay line 1 this stable condition would be with current flowing in valve 20. The application of a positive pulse to the control grid 21 of valve 19 causes the multivibrator circuit to trip over, current flowing in valve 19 and ceasing in valve 20. The arrangement returns to its stable condition after a time interval depending upon the time constant of the circuit CR_1R_2 as is well known, and this time constant which determines the durations of the pulses may be adjusted by adjusting the bias voltage on control grid 22 of valve 20 by means of a source of potential 23 for example. The intelligence wave of the channel to be transmitted for example, from a microphone 24 is applied at terminals 25 to the grid 22 and varies the duration of the generated pulses in accordance with the ampli-

tude of the wave. There is thus obtained across the cathode resistance 26 of valve 20 a series of negative pulses whose trailing edge is steep and duration modulated in accordance with the amplitude of the intelligence wave. Such a wave is indicated at 27. This wave is differentiated by means of capacity 28 and resistances 29 or any other known type of differentiating circuit to produce short negative and positive pulses as indicated at 30. The negative pulse is eliminated by the diode or rectifier 31 or other known type of eliminator and the positive pulse, time modulated in accordance with the intelligence wave amplitude is passed to the conductor 32 in which it is mixed in the series of pulses obtained from the other channels. The combined pulse train is then transmitted through the desired medium to the receiver. The time phased pulses indicated at 33 of the respective channels and the synchronising pulses such for example as indicated at 34 are fed to the line 32 through diodes or other one-way devices 35—40 which isolate the channel equipments from each other.

In this example taken, it will be observed that it is not necessary to have the additional valve 10, since the leading edge only of the pulse is employed to trigger the multivibrator. The valve 19 is shown as having a source 41 of biasing voltage which is adjusted to such value that the pulse applied to the control grid 21 trips the multivibrator circuit as the pulse passes through a voltage value at the correct moment. The time constant of the multivibrator circuit may then be correctly adjusted by means of the source 23.

In cases, however, such as where the valve 20 may be common to a plurality of multivibrators associated with respective channels and it is necessary to adjust the bias of valve 19 differently for the respective channels it will be necessary to provide for each of the channels a valve 10 and its associated circuits as hereinbefore described, the output pulses obtained from valves 10 being applied to the grid of the valve 19 which will be tripped successively by the pulses from the valves 10.

If the amplitude of the pulses obtained from the delay network varies more than is allowable from the original input amplitude or if the network produces abnormal distortions of the pulse shape as described with reference to Figure 1, as the tapping points are more remote from the input terminals, correct timing of the derived pulse may be obtained by taking the "slice" of the pulse obtained from the network 1, from which slice the derived pulse is developed, at a suitable voltage level. This may be effected by suitably biasing the valve 10, or 19 as the case may be, to which the pulse from the network 1 is applied.

Furthermore, in order to vary the channel period, for example by increasing the period of one channel at the expense of reducing the period of the next successive channel, the leading or trailing edge of the derived pulse may be advanced or retarded by taking the slice of the pulse from the network from which slice the derived pulse is developed, at a suitable voltage level.

The derived pulses from the output of the valves 10 may be used to develop further pulses of short constant duration, for example by differentiating the pulses in the output of 10, which short pulses define the beginning of the respective channel periods. Alternatively longer pulses whose respective durations are equal to the periods of the respective channels may be used

to define the channel periods or the leading or trailing edge of a derived pulse may be used to define the beginning of a channel period. Such an arrangement may be similar to that shown in the rectangle 15 of channel 7 without the input speech arrangement 24, 25 and the multivibrator time constant adjusted to have the same value as the respective channel periods.

Any known type of generator of pulses of rectangular waveform may be employed to feed the delay line 1. A power pulse generator giving pulses of great amplitude for example as that described in the aforementioned United States application Ser. No. 602,450 is suitable. In the example illustrated in Figure 2 this pulse generator takes the form of the well known multivibrator circuit 42 comprising two interconnected discharge valves 43, 44 so shown.

The voltage limits between which the "slice" of the pulses is taken by valves 10 and 19 are approximately equal to the cut-off voltage and the voltage at which grid current appears, and the difference is equal to about 5 volts for a high slope valve (i. e. a valve having a steep anode current grid voltage characteristic) such as a pentode and pulses of an amplitude at least 10 times greater should be fed to the input of the delay network.

If the network for producing trapezoidal wave form pulses is included in the cathode circuit, for example, as described in the aforementioned United States application Ser. No. 602,804, pulses of much greater amplitude are required. Since the impedance of the delay network is always low, some thousands of ohms usually, a high power pulse generator is required. Such a generator may be for example, the power multivibrator circuit described in the aforementioned United States application Ser. No. 602,450.

The multivibrator arrangement is designed to produce rectangular pulses at a repetition period substantially equal to the distributor period and may be stabilised to this end in any well known manner. As shown in Figure 1 the oscillation generator 42 may be synchronised by the pulse from the output 45 of the delay line 1 after amplification and re-shaping, if necessary, in an amplifying valve 46, the output of which is fed to the control grid of one of the valves 43, 44 depending upon the sign of the pulses, positive or negative, to control the generator as will be understood by those versed in the art. Thus by synchronising the input by the output of the delay line, it is ensured that only one pulse can be present at any one time in the delay line and consequently no two channels can possibly be alive at any one instant.

The output from the multivibrator 42 is taken from a resistance 47 in the cathode circuit of valve 44, the pulses having the form shown at 34, and being used for transmission as synchronising pulses for use at the receiver, as well as for feeding into the delay line 1.

Whilst only the arrangement at a transmitter has been described it will be understood by those versed in the art, that such an arrangement as shown in Figure 2 is equally applicable at the receiver, the apparatus represented by blocks 13—17 then being receiving apparatus, the outputs from the valves 10 usually being fed to control suitable gating circuits, and the outputs from the equipment represented by blocks 13—17 being fed to respective translating apparatus, for example, telephone receivers or other work apparatus.

In the block diagram shown in Figure 3, like members or circuit elements as in Figure 2 are given the same reference characters as in that figure.

The master multivibrator pulse generator 42 feeds pulses at the distributor cyclic frequency to the input terminals 4 of the distributor delay network 1, and the output pulses from the delay network output terminals 45 are fed back to the master pulse generator 42 for stabilising this latter. The block 48 represents a master oscillator which has a very stable frequency and may be for example a piezo-electric crystal controlled oscillation generator, of which many are well known in the art. This master oscillator 48 is designed to have a frequency which is a harmonic of the desired distributor frequency multiplied by half the number of channels. The oscillations generated in 48 are fed to a circuit arrangement represented by block 49 for squaring the sine wave oscillations fed thereto. This squaring arrangement may comprise an electron discharge amplifying tube biased to work at anode current saturation for positive potentials applied to its control grid, or a multivibrator circuit having two stable conditions, arranged to be triggered by the sinusoidal wave from 48 as it passes through zero or other prearranged value. The output from the squaring circuit 49 is fed to the master multivibrator. The output from the squaring circuit 49 is reversed in phase, or otherwise delayed by one half-period of the master oscillator to provide the two outputs as indicated at 50 and 51 delayed the one with respect to the other by a half period. If the squaring device 49 comprises a multivibrator type of circuit, the two outputs may be obtained directly, for example, one from the cathode circuit and the other from the anode circuit of the output valves. These outputs may be, and preferably are, passed through a purifying amplifier to obtain the desired pure rectangular wave forms. Such a purifying amplifier comprises an electron discharge amplifier arranged to cut a slice, so to speak from the applied pulses. The outputs 50 and 51 are applied to the alternate channel equipments 1, 3, 5 etc. and 2, 4, 6 etc. together with the outputs from the respective points 5, 7, etc. and 6, 8 etc. respectively of the delay network, so that the pulses 50 or 51 and the pulses from delay network 1 are effectively in series.

It will be observed that the pulses from the respective points of the delay network will occur concurrently with the pulse in the train 50 or 51 as the case might be and that only one channel equipment will be operated at any one time. As the pulse from the master multivibrator passes down the delay network it selects the channels successively.

The operation of the arrangement shown in Figure 3 will be made clearer by reference to Figure 4.

Curve *a* represents one of the series of pulses 50 or 51 obtained from the output of the squaring device or square pulse generator 49. The group of curves designated *b* represent the selector pulses for alternate channels, namely channels 1, 3, 5, 7, which are obtained from respective points 5, 7, etc. of the delay network 1. These selector pulses are shown as getting more and more distorted as they advance along the delay network and the distortion is shown of course much exaggerated, for the sake of clarity. Furthermore, it will be observed that the channel selector pulses are of longer duration than the

duration of the period allotted to each channel. These channel periods are indicated by the vertical broken lines. It will be further observed that the channel durations are defined by the durations of the auxiliary pulses represented in curve *a*. Curve *c* shows the resultant curve after combining, or adding curve *a* and curve *b* for channel 5. Similar curves will be obtained for the other channels. The wave form of curve *c* is obtained in practice as already stated by feeding the voltages represented by curves *a* and *b* effectively in series, for example, to an electron discharge amplifier. In such an arrangement, one wave form may be applied to one grid and the other wave form to the other grid, or both wave forms may be applied so that their voltages add together, on the same grid. The output wave form of the amplifier is then given by curve *c*. The amplifier 10 in Figure 2 or the valve 19 of modulator 18 (block 15), Figure 2, may perform this function. This amplifier is so biassed, however, as to cut a slice, so to speak, between the lines 52 and 53. This is done by negatively biassing the amplifier so that it commences to pass current at the voltage represented by line 52 and is at saturation at the voltage represented by line 53. The resulting wave form in the output circuit of the valve is then represented by curve *d*, from which it will be observed that a pulse of rectangular wave form, exactly defining the channel width is obtained. This pulse is then applied as the selector pulse to operate the channel modulator at the transmitter or the gating circuit or demodulator at the receiver in known manner.

In the arrangements at the receiver, the master oscillator 48 may not be required, and its function may be performed by the synchronising pulses, means being provided to derive from the selector pulse frequency, the desired harmonic corresponding to the frequency of the pulse train 50 or 51. Alternatively, the synchronising pulses may be employed to synchronise the master multivibrator at the receiver in addition to the feedback pulses and pulses derived from the squaring arrangement.

In a modification of the arrangement described in connection with Figures 3 and 4, the modulating and demodulating arrangements at the transmitter and receiver respectively may be such as only to require marking pulses to mark the beginning and ends of the respective channels, or when the whole distributor cycle is occupied completely by channel periods without any time interval between the ending of one channel and the commencement of the next, only the marking pulses marking the commencement of the channels may be required. These marking pulses may be obtained by differentiating the output pulses from the squaring device 49, or by utilising a suitably designed multivibrator type of circuit having one stable condition and of small time constant arranged to be triggered into the unstable condition by the sine waves from the oscillator 48 or equivalent source of the desired frequency, such as a harmonic generator fed by synchronising pulses at the receiver as will be understood by those versed in the art. The channel equipment at the transmitter and receiver may then comprise a circuit arrangement arranged to be triggered to one condition of stability by the selector marking pulse and into the other condition of stability by the channel pulses. Such an arrangement may be as described in the aforementioned United States application Ser. No. 602,804.

What is claimed is:

1. In a multi-channel electrical communication system in which the intelligence wave of each channel is transmitted as a modulation of a series of electrical pulses, a distributor system comprising a delay network, means associated therewith to provide timed phase pulses for rendering the channels cyclically and successively operative, means for applying to the respective channel equipments auxiliary electrical pulses of rectangular wave form whose durations define the channel periods, said auxiliary pulses having a repetition frequency equal to the number of channels fed in parallel multiplied by the distributor frequency, said channel equipments being arranged so as to be operated only when a distributor selector pulse and an auxiliary electrical pulse occur together at said channel equipments.

2. In a multi-channel electrical communication system in which the intelligence wave of each channel is transmitted as a modulation of a series of electrical pulses, a distributor system comprising a delay network, means associated therewith to provide timed phase pulses for rendering the channels cyclically and successively operative, means for applying to the respective channel equipments auxiliary electrical pulses of rectangular wave form whose durations define the channel periods, said auxiliary pulses being applied to the equipments of alternate channels in parallel and having a repetition frequency equal to one-half the number of channels multiplied by the distributor frequency, the auxiliary pulses applied to one set of channel equipments being timed phased by one-half of the repetition period with respect to the auxiliary pulses applied to the alternate set of channel equipments, said channel equipments being arranged so as to be operated only when a distributor selector pulse and an auxiliary pulse occur together at said channel equipments.

3. In a multi-channel electrical communication system in which the intelligence wave of each channel is transmitted as a modulation of a series of electrical pulses a distributor system

comprising a delay network, means associated therewith to provide timed phase pulses for rendering the channels cyclically and successively operative, means for applying to the respective channel equipments auxiliary electrical pulses which define the channel periods, said auxiliary pulses having a repetition frequency equal to the number of channels fed in parallel multiplied by the distributor frequency, said channel equipments being arranged so as to be operated only when a distributor selector pulse and an auxiliary electrical pulse occur together at said channel equipments.

4. In a multi-channel electrical communication system in which the intelligence wave of each channel is transmitted as a modulation of a series of electrical pulses a distributor system comprising a delay network, means associated therewith to provide timed phase pulses for rendering the channels cyclically and successively operative, means for applying to the respective channel equipments auxiliary electrical pulses whose durations define the channel periods, said auxiliary pulses having a repetition frequency equal to the number of channels fed in parallel multiplied by the distributor frequency, said channel equipments being arranged so as to be operated only when a distributor selector pulse and an auxiliary electrical pulse occur together at said channel equipments.
